UNITED STATES PATENT OFFICE

107,270

DESIGN FOR AN AIR HEATER UNIT

Melvin M. Tilley, San Rafael, Calif., assignor to
H. C. Little Burner Co., Inc., San Rafael, Calif.,
a corporation of California

Application September 13, 1937, Serial No. 71,585

Term of patent 7 years

To all whom it may concern:

Be it known that I, Melvin M. Tilley, a citizen of the United States and a resident of the city of San Rafael, county of Marin, State of California, have invented a new, original, and ornamental Design for an Air Heater Unit, of which the following is a specification, reference being had to the accompanying drawing, forming part thereof.

Referring to the drawing:

The single figure of the drawing is a perspective view showing an air heater unit incorporating my new design.

The other end is like the end shown in this drawing.

I claim:

The ornamental design for an air heater unit substantially as shown and described.

MELVIN M. TILLEY.
